LEADING EDGE GAUGE FOR TYPEWRITING MACHINES

Claude Wellington Brumhill, Leicester, England,
assignor to The Imperial Typewriter Company,
Limited, Leicester, England

Application February 24, 1943, Serial No. 476,971
In Great Britain November 27, 1942

6 Claims. (Cl. 197—126)

This invention relates to typewriting machine carriages of the type having a platen sub-frame carrying the platen and mounted on the carriage for displacement of the platen between operative and inoperative positions, a paper support arm projecting from the sub-frame, and a paper stop or leading edge gauge adjustable on said arm towards and away from the platen, and wherein the platen is displaceable to the inoperative position by a forward pull exerted on said arm by the operator. Such carriages are commonly employed in manifolding or continuous stationery machines, i. e. machines drawing their paper as a continuous multi-ply web from a bulk supply thereof (often a zig-zag pile). In operation, the paper, interleaved with carbon or like sheets, is fed round the platen and typing continues until at the end of the requisite length thereof the leading edge of paper abuts on the leading edge gauge. The operator then grips the leading margin of paper against the paper support arm adjacent to the gauge, pulls on the arm to displace the platen to inoperative position, causes the carbons to be retracted between the plies of paper thus released from the feeding grip of the platen, and then restores the platen. The chief object of the present invention is the elimination of certain difficulties (hereinafter explained) that have been experienced in the use of carriages of the aforesaid type having a pivoted sub-frame, although it is considered that the utility of the invention is not restricted to pivoted sub-frames.

According to this invention, a typewriting machine carriage of the type specified is characterised in that the leading edge gauge has its paper-engaging part (i. e. that part against which the leading edge of the paper abuts and which therefore serves as the gauge proper) offset towards one side of the paper-support arm in such manner as to leave room for the operator to grip the extreme margin of the paper against said arm. The said part is preferably wholly offset beyond the side of the arm. According to an important feature of the invention the gauge is void of any thumb-engaging edges or corners at the front of the arm (that is, edges or corners that in forward movement of the arm would engage the side of the operator's thumb gripping the paper against the arm). Since a thumb-engaging surface is difficult to avoid, it is preferred that such surface shall present a convexity away from the aforesaid paper-engaging part.

The and other features of the invention set out in the appended claims are incorporated in the construction which will now be described, as

an example, with reference to the accompanying drawings, in which

Figure 1 is an end view of a typewriter carriage incorporating the present invention,

5 Figure 2 is a front elevation, on a larger scale, of a portion of the paper support arm, including the leading edge gauge.

Figure 3 is a cross section on the line 3—3 in Fig. 2.

10 Figure 4 is a longitudinal section through the paper support arm and gauge shown in Fig. 2, while

Figure 5 is a diagram illustrating the use of the gauge.

15 In Figure 1 the invention is shown as applied to the typewriter carriage described in British patent specification 548,198. For details reference may be made to said specification, but a brief description will be given herein and accorded the same reference numerals. The typewriter carriage 10 has, pivoted at the front thereof at 22 between the carriage ends 23, a sub-frame consisting of platen end plates 20 connected by a knife 21 in which sub-frame the

20 platen 11 is mounted by the platen spindle 19. The said sub-frame is displaceable about its pivot 22 (the axis of displacement being parallel to but in advance of that of the platen) by means of the paper support arm 30 to swing the platen 11 upwards and forwards away from the co-operating feed rollers 25, 26 and the paper tray 24 so that the feeding grip on the web of paper is relaxed. This displacement is effected by hand, the operator gripping the margin of the paper

25 against the paper support arm 30 as illustrated in Fig. 5, and pulling the support arm forward. At each end of the sub-frame there is a lever 36 pivoted at 35 said levers being connected by a tubular member 37 to which the support arm 30

30 is attached. Thus when the support arm 30 is pulled forward said levers 36 are rocked about pivots 35 against the action of springs 38, the extent of movement being restricted by screws 42 passing through slots 41. At least one lever

36 carries a projecting stud or roller 39 which is thus brought into contact with a platen clamping lever 40 associated with a platen clamp 32, said clamp and lever being pivoted to the carriage end 23 at 33 and being drawn by a spring 34 so that the clamp 32 normally overlies a roller 45 on the platen spindle 19. The lever 40 and clamp 32 are thereby moved to the left in Fig. 1, the extent of movement being determined by a screw 42' extending through a slot 43 into the carriage end. The pull on support arm 30 there-

fore unlocks the platen clamping mechanism and swings the platen upwards and forwards. In the return movement of the platen to its operative position the roller 45 on the spindle 19 makes contact with the arm 40 and displaces the clamp 32 to such an extent that the platen spindle 19 can pass freely into the cradles 46 provided for its reception in the carriage ends 23. In the forward movement of the paper support arm 30 the operators' thumb T, gripping against said support arm that margin of the paper that abuts on the gauge 31, tends to pivot or rock and if the gauge is of the shape shown in the aforesaid patent specification this causes the right-hand edge of the gauge to bite into the thumb and tends to cause the operator's grip on the margin of the paper to relax, and a similar disadvantageous finger contact is established with that part of the gauge that projects at the back of arm 30. It is further to be pointed out that under wartime conditions there is a tendency for the untyped margin of paper (that is to say the portion between the extreme edge of the paper and the extreme edge C of the carbons, as shown in Fig. 5) to be reduced to the minimum. Therefore if the paper-engaging part of the gauge extends across the width of the paper support arm 30 as in the said specification there is further a danger that the gripping thumb will overlap the carbons. These difficulties are overcome in the present invention. The gauge indicated generally at 31 has its paper-engaging part 31a wholly offset to the left-hand side of the paper support arm 30 so that plenty of room is left for the thumb T. Additionally, the gauge is void of any thumb-engaging edges or corners and the thumb-engaging surface 31b presents a convexity away from the paper-engaging part 31a. This effect is achieved by causing the surface of the sheet metal of which the part 31a is formed (which surface projects at right angles to the arm 30) to blend in a smooth curve around the axis of a clamping screw 52. More specifically, the sheet metal is bent round and grips a tapped boss 50 which projects from a slider 51 and houses the screw 52. It is also pointed out that the sheet material of which the part 31b is formed is cranked so that the clamping screw and its boss are spaced further from the platen 11 than is said part 31a, thereby giving more room for the thumb. The paper support arm 30 is channel shaped in section as shown in Fig. 3, with inturned margins or gibs 30a constituting a dovetailed channel in which the slider 51 may be adjusted lengthwise to any desired position in which it may be clamped by the screw 52. This construction obviates any portion of the gauge projecting at the back of the paper support arm 30, where it may cut or interfere with the operator's fingers, and permits the rear surface of the arm 30 to be smooth.

The gauge also incorporates a forwardly projecting lip or edge 53, which is preferably serrated or scalloped (as exemplified in Fig. 2), against which the paper may be gripped by the thumb. This provides a firm grip even though the margin of paper may be small. Preferably the spacing between this edge 53 and the part 31b is adjustable in the direction of the length of the arm 30. To this end the edge 53 is formed on a plate member 54 which extends slidably between the slider 51 and the front face of the channel in said arm 30, the said plate member 54 being engaged by the end of the screw 52. It will thus be seen that by slackening off screw 52 not only may the gauge as a whole be adjusted

along the arm 30, but the position of the edge 53 in relation to the part 31b may be adjusted, said gauge and edge being clamped by tightening up the screw 52. The lip or edge 53 provides a well 55, between it and the boss 50 as shown in Fig. 4, which enhances the grip on the paper web. In order to prevent the plate member 54 from becoming detached its upper edge may be given an out-turned lip 54a.

10 The paper-support arm and gauge may be sold, as replacements or spare parts, separately from the carriage, and therefore the invention includes said arm and gauge.

I claim:

1. In a typewriting machine carriage having a platen sub-frame carrying the platen, and a paper support arm projecting from the sub-frame, a leading edge gauge mounted on the arm for adjustment along it which gauge has a paper-engaging part offset at one side of the arm leaving room for the operator to press the extreme margin of the paper towards the arm with his thumb, a tapped boss on the gauge projecting at the forward face of the arm at a location further from the platen than the said part, a connection integral with the said part for connecting it to the boss and blending in a smooth curve around the axis of the boss, and a clamping screw in the boss for clamping the gauge in the desired position of adjustment along the arm.

2. In a typewriting machine carriage having a platen-carrying sub-frame and a paper support arm extending therefrom: a leading edge gauge comprising a portion longitudinally adjustably secured to said arm and projecting forwardly therefrom, said portion presenting a smooth curved surface for preventing injury to the operator's hand when manually gripping the paper; a paper-stop portion laterally offset from said securing portion whereby the paper may be gripped adjacent the securing portion without engagement between the hand and said stop portion; and a member presenting an edge at the front of said support arm against which the paper may be gripped, said member being adjustable relative to the other portions of the gauge in a direction longitudinal of the support arm.

3. A leading edge gauge for a typewriting machine carriage having a platen-carrying sub-frame and a paper support arm extending therefrom, said gauge comprising a slider member mountable on said support arm for adjustment longitudinally thereof; means for securing said member to the arm; and a paper-stop element carried by said slider member, comprising a portion projecting forwardly from said member and presenting a smooth convex surface for preventing injury to the operator's thumb when gripping the paper adjacent thereto, and a paper-engaging portion extending laterally from said first named portion.

4. A leading edge gauge for a typewriter machine carriage having a platen-carrying sub-frame and paper support arm extending therefrom, said gauge comprising a slider member mountable on said support arm for adjustment longitudinally thereof; means for securing said member to the arm; and a paper-stop element comprising a substantially cylindrical portion extending from the forward face of the slider member and presenting a smooth convex thumb-engaging surface, and a paper-engaging portion extending from and offset both laterally and longitudinally with respect to said cylindrical portion, all parts of said gauge being disposable for-

wardly of the plane of the rear face of the support arm.

5. A typewriting machine carriage of the type specified, having a paper-support arm the front face of which is formed longitudinally with a dove-tailed channel, a slider slideable along the channel and having a tapped boss projecting forward from it, a plate member located between said slider and the face of the channel and movable relatively to the slider, a clamping screw in the tapped boss for bearing against the plate member to clamp the latter and the slider to one another and to the arm, a paper-engaging part offset to the left-hand side of the arm at a location nearer to the platen than the said boss and having a connection to said boss, and a forwardly-projecting paper-grip lip or edge at that

end of the plate member which is nearest to the platen.

6. In a typewriting machine carriage having a platen-carrying sub-frame, and a paper support arm extending therefrom: a leading edge gauge having a portion longitudinally adjustably secured to said arm and projecting forwardly therefrom, said gauge also having a paper stop portion laterally and longitudinally offset from said securing portion whereby the operator may manually grip the paper against the arm adjacent the securing portion without contact between his hand and said stop portion, and said securing portion being convexly formed to prevent injury to the operator's hand in such gripping.

CLAUDE WELLINGTON BRUMHILL.
